UNITED STATES PATENT OFFICE

2,572,813

LAMP SOCKET ASSEMBLY AND APERTURED SUPPORT

Howard J. Murphy, Lynnfield, Mass., assignor to
 United-Carr Fastener Corporation, Cambridge,
 Mass., a corporation of Massachusetts

Application April 25, 1949, Serial No. 89,427

10 Claims. (Cl. 173—339)

1

This invention relates to lamp socket assemblies for automobile lighting and the like, and aims generally to improve lamp socket assemblies of the type adapted to be inserted in an apertured support and releasably locked therein by turning.

One of the primary objects of this invention is the provision of a lamp socket assembly for automobile lighting and the like which is simple in construction, economical to manufacture and easy to assemble and install.

A further object of the invention is the improvement of lamp socket assemblies of the turn-in type wherein the socket-carrying member may be readily mounted in an apertured supporting member by a simple manipulative procedure and releasably locked therein by a resilient locking member designed to yieldably hold the socket-carrying member firmly positioned against the apertured supporting member so as to be substantially unaffected by vibration.

A further object of the invention is the provision of a lamp socket assembly having a resilient locking member provided with portions thereon adapted to engage the under surface of an apertured support to yieldably hold the socket assembly firmly thereagainst and provided with other portions adapted to seat in notches in the apertured support to releasably lock the socket assembly thereto.

A still further object of the invention is the provision of a lamp socket assembly of the turn-in type provided with a socket-carrying member and a resilient locking member wherein the resilient locking member is held in assembled relationship with the socket-carrying member by an apertured ring member provided with inturned spring fingers adapted to position the assembly in an apertured support.

Another object of the invention is the improvement of lamp socket assemblies of the turn-in type having a socket-carrying member wherein the socket-carrying member is provided with a wing nut construction to facilitate mounting the assembly in an apertured support.

Still another object of the invention is the provision of a lamp socket assembly having outwardly extending inturned spring fingers adapted to position the assembly in an apertured support and a resilient locking ring having portions thereof yieldably engaging opposite sides of the flanged support to releasably secure the socket assembly thereto.

A further object of the invention is the provision of a supporting sleeve member adapted to be attached to an apertured support and carry-

2

ing a lamp socket assembly of the turn-in type releasably locked in one end thereof.

The above and other objects and advantages of the invention will be apparent to persons skilled in the art to which the invention relates from a consideration of the accompanying drawings and annexed specification illustrating and describing a preferred embodiment of the invention.

10 In the drawings:

Fig. 1 is a side view of the unitary socket assembly according to the present invention mounted in a supporting base member;

Fig. 2 is an enlarged sectional view taken on the line 2—2 of Fig. 1;

Fig. 3 is an end view of the supporting base member;

Fig. 4 is a sectional view taken on the line 4—4 of Fig. 3;

20 Fig. 5 is a side elevational view of the unitary socket assembly;

Fig. 6 is an end view of the unitary socket assembly looking from the right in Fig. 5;

Fig. 7 is an end view of the unitary socket assembly looking from the left in Fig. 5;

Fig. 8 is a perspective view of the unitary socket assembly with the parts in disassembled relationship;

Fig. 9 is a plan view of the fastening and positioning member;

30 Fig. 10 is a side view of the fastening and positioning member looking from the left in Fig. 9;

Fig. 11 is a side view of the fastening and positioning member looking from the top in Fig. 9;

Fig. 12 is a plan view of the tensioning and ring;

Fig. 13 is a side view of the tensioning and locking ring looking from the left in Fig. 12;

40 Fig. 14 is a side view of the tensioning and locking ring looking from the top in Fig. 12;

Fig. 15 is a perspective view of a modified form of socket assembly in accordance with the present invention;

45 Fig. 16 is a perspective view of the fastening and positioning member of Fig. 15;

Fig. 17 is a perspective view of the ring member of Fig. 15;

Fig. 18 is a cross-sectional view of the embodiment of the invention shown in Fig. 1, showing the locking ring engaging the support;

Fig. 19 is a cross-sectional view taken on line 19—19 of Fig. 18, showing the unitary socket assembly locked to the support;

55 Fig. 20 is a cross-sectional view similar to Fig.

19, showing the unitary socket assembly in position for insertion into the aperture of the support;

Fig. 21 is a partial cross-sectional view taken on line 21—21 of Fig. 19;

Fig. 22 is a partial cross-sectional view taken on the line 22—22 of Fig. 19;

Fig. 23 is a partial cross-sectional view taken on line 23—23 of Fig. 20;

Fig. 24 is a partial cross-sectional view taken on line 24—24 of Fig. 20; and

Fig. 25 is a partial cross-sectional view taken on line 25—25 of Fig. 20.

Referring now to the drawings, the improved socket assembly of the present invention comprises a unitary socket assembly 1 adapted to be releasably locked in a supporting base member 2 having a flanged portion 3 for attachment to an apertured support S or the like as by the studs 4. The supporting base member 2 may desirably be formed with a supporting sleeve 5 adapted to receive the socket assembly 1, and having an inturned flange 6 provided with radial recesses or notches 7 adapted to releasably receive and hold the socket assembly in locked position in the sleeve. It will be apparent that the assembled device may readily be installed on the dash or instrument panel or other panel or support of an automobile or other machine to provide a protected lamp socket assembly substantially unaffected by vibration.

The unitary socket assembly 1 comprises a carrier or manipulative handling part 8 provided with a substantially cylindrical body portion 9 adapted to snugly receive a lamp socket 10 and a base portion 11 adapted to seat a resilient tensioning and locking ring 12 and a carrier fastening and positioning member 13, and having an upturned flange 14 adapted to be turned inwardly and downwardly over the outer edges of the member 13 to securely hold it in place. The substantially cylindrical portion 9 of the carrier 8 has laterally extending flattened portions 15 and 16 providing a wing nut effect to facilitate manual manipulation of the socket assembly 1 when mounting it in the supporting base member 2.

The lamp socket 10 may have a press fit with the body portion 9 of the carrier 8 and is adapted to support therein a contact-carrying plug of insulating material such as Bakelite or the like (not shown) with the portion thereof carrying the lead wires projecting through the opening 18 in the end of the body portion 9. Indentations 19 in the socket 10 assist in retaining the Bakelite plug in position therein. The portion of the socket 10 projecting from the carrier 8 is adapted to receive an electric light bulb or lamp of well known construction and may be provided with the usual outwardly grooved portions 20 and 21 for cooperation with the usual pins on the lamp base to releasably lock it in position.

The fastening and positioning member 13 comprises a ring portion 22 provided with laterally extending inturned spring fingers 23 adapted to engage the inner edge of the opening defined by the flanged portion 6 and thus position the unitary socket assembly 1 in the supporting base member 2. The ring portion 22 is adapted to be seated on the base portion 11 of the carrier 8, as pointed out above, and to be clamped thereon by the flange 14 being turned inwardly thereover. The member 13 is further provided with openings 24, 25, 26 and 27, which extend out-

wardly into the ring portion 22 and upwardly into the spring fingers 23 for receiving the ears 29, 30, 31 and 32 of the resilient tensioning and locking ring 12.

The openings 26 and 27 extend upwardly into the spring fingers 23 to a depth sufficient to permit the ears 31 and 32 of the ring 12 to be sprung outwardly from the base 11 into sliding engagement with the inner surface of the flange 6 of the supporting base member 2. The ears 29 and 30 are confined rather closely to the base member 11 by the more shallow openings 24 and 25 in the spring fingers 23 and are placed under tension when the ears 31 and 32 are sprung outwardly as aforesaid. This urges the ears 29 and 30 and hence the members 8 and 13 into firm engagement with the outer surface of the flange 6 and securely holds the parts in assembled relationship substantially unaffected by any vibration to which it may be subjected.

The tensioning and positioning ring 12 may desirably be made of resilient material such as spring metal or the like and is preferably bent or otherwise deformed so that the ears 31 and 32 are offset laterally with respect to the ears 29 and 30. Thus when the ring 12 is assembled with the carrier 8 and member 13 with the ring portion 28 thereof positioned inwardly of the member 13, the ears 31 and 32 will be spaced normally outwardly somewhat from the base portion 11. This construction plus the outwardly curved shape of the edges 33 of the ears 31 and 32 facilitates engagement of the ears 31 and 32 with the inner surface of the flange 6 when the unitary lamp socket assembly is mounted on the supporting base member 2.

The ears 29 and 30 may desirably be offset slightly from the ring portion 28 by bending or the like so that the outer surfaces thereof will project beyond the inturned flange 14 and have a resilient bearing contact with the outer surface of the flange 6. The ears 29 and 30 may further desirably have one edge thereof turned inwardly toward and then outwardly in the plane of the ring portion 28, as shown at 34 and 35, to facilitate removal of the unitary socket assembly 1 from locking engagement with the supporting base member 2 as will be apparent hereinafter.

In assembling the device of Figs. 1 to 14, the lamp socket 10, with or without a suitable contact plug mounted therein, is forced into the cylindrical body portion 9 to form a press fit therewith. The positioning member 13 and locking ring 12 are then mounted on the base portion 11 with the ears 29 and 30 positioned in the openings 24 and 25, and the ears 31 and 32 positioned in the openings 26 and 27. The flange 14 is then turned inwardly over the ring portion 22 to hold the members 12 and 13 in assembled relationship. When so assembled, the ears 29 and 30 are held closely adjacent the base 11 with the offset body portion thereof slightly spaced from the base 11 and projecting slightly beyond the flange 14 to form a bearing surface with the outer edge of the flange 6 and with the inturned edges 34 and 35 thereof in contact with the base 11 to facilitate the unlocking operation. The ears 31 and 32 are spaced outwardly from the base portion 11 sufficiently so that the curved edges 33 thereof may engage the edges of the notches 7 to spring the ears 31 and 32 outwardly into engagement with the inner surface of the flange 6 when the socket is rotated.

In mounting the unitary socket assembly 1 on the supporting base member 2, as shown in de-

tail in Figs. 18 through 25, the assembly 1 is grasped by the wing nut portions 15 and 16, and the socket end thereof inserted into the sleeve 5 through the flanged portion 6 with the ears 31 and 32 resting in the radial notches 7, see Figs. 20 and 24, and the ears 29 and 30 resting on the outer surface of the flange portion 6, see Figs. 20 and 25. The assembly is then rotated in a clock-wise direction until the ears 31 and 32 are positioned beneath the flange 6, see Figs. 19 and 21, this operation being facilitated as hereinbefore stated, by the curved edges 33 of the ears 31 and 32 striking the edges of notches 7 when the assembly is rotated, thus forcing the ears 31 and 32 outwardly in the openings 26 and 27 and away from the base portion 41 against the spring action of the ring portion 28 so that they may slide into position behind the flange 6. When so assembled, the inherent resiliency of the locking ring 12 urges the ears 29 and 30 towards the ears 31 and 32 so that the flange 6 of the supporting base member 2 is firmly gripped therebetween to securely hold the parts in assembled relationship with the lamp receiving socket 10 positioned within the sleeve 5. At the same time the carrier 8 and member 43 are firmly held against the flange 6 by virtue of the coaction between the ears 29 and 30 and the shallow openings 24 and 25 in the spring fingers 23. The socket assembly 1 may be quickly and easily removed from the supporting base member 2 merely by rotating it in a left-hand or counterclockwise direction until the ears 31 and 32 enter the notches 7 and then pulling outwardly.

A further feature of this invention resides in a releasable locking action which is obtained by mounting the socket assembly 1 on the supporting base member 2, as aforesaid, and then rotating it clockwise through a quarter turn or until the ears 29 and 30 are positioned opposite the notches 7. When this happens, the inherent resiliency of the ring 12 and the pull exerted by the ears 31 and 32 causes the ears 29 and 30 to snap into the notches 7 thereby to lock releasably the assembly in position. When it is desired to release the socket assembly from locked position, it is merely necessary to turn it counterclockwise through a quarter turn and then remove it as before. Counterclockwise rotation from locked position is facilitated by the inwardly turned edges 34 and 35 of the ears 29 and 30 which ride outwardly over the edges of notches 7 to position against the ears 29 and 30 on the outer surface of the flange 6. It will be apparent that in the locked position of the assembly just described the positioning of the ears 31 and 32 of the resilient ring 12 on the inner side of flange 14 serves to draw the assembly into close contact with the supporting base member and to securely hold it there.

In a modified form of the invention shown in Figs. 15 to 17, the carrier 40 has a substantially cylindrical portion 41 adapted to snugly receive the socket 42 and a flanged portion 43 adapted to seat the fastening and positioning member 44 and the tensioning and locking ring 45. A lip 46 on the flanged portion 43 is adapted to be turned inwardly over the rim of the member 44 to clamp the parts in assembled relationship. The carrier 40 further has an end portion 46, which may be removable if desired, for receiving a plug of Bakelite or the like containing the lead-in wires and contacts for the lamp-receiving socket 42.

The fastening and positioning member 44 has a ring portion 47, inwardly turned spring fingers 48, 49, 50 and 51, and openings 52, 53, 54 and 55 similar to the member 13 hereinbefore described. Member 44 is additionally provided with outwardly extending ears 56 and 57 having downturned flaps 58 and 59. When the device is assembled, the ears 56 and 57 are turned downwardly, as shown in Fig. 15, to form finger-engaging grips adapted to facilitate manipulative handling of the device during assembly with or disassembly from an apertured support.

The tensioning and locking ring 45 functions similarly to the ring 12 hereinbefore described but differs therefrom structurally in that the ears 60 and 61 are bent laterally out of the plane of the ring portion 62 to form cam surfaces 63 and 64, and the ears 65 and 66 are provided with upturned locking lugs 67 and 68 having tapered edges 69 and 70. The device of Figs. 15 to 17 is assembled similarly to the device of Figs. 1 to 14 with the ears 60 and 61 positioned in the openings 53 and 55 and the ears 65 and 66 positioned in the openings 52 and 54.

In mounting the device on a supporting base member such as that previously described, the ears 60 and 61 are positioned in the notches 7 and the assembly rotated by means of the finger-engaging portions 56 and 57. This causes the cam surfaces 63 and 64 to contact the edges of notches 7 so that the ears 60 and 61 ride outwardly thereover and into locking position on the inner surface of the flange 6. At the same time, the locking lugs 67 and 68 are in contact with the outer surface of the flange 6, thereby securing the assembly to the flange. Rotation of the socket assembly through a quarter turn positions the locking lugs 67 and 68 in the notches 7 to releasably lock the assembly on the supporting base member as before. Removal of the socket assembly is readily accomplished by rotating it one quarter turn in a left-hand or counterclockwise direction, the tapered edges 69 and 70 acting as cams to facilitate removal of the locking lugs 67 and 68 from the notches 7.

It will thus be seen that this invention provides improved socket assemblies for automobile lighting and the like which are simple in construction, easy to assemble and install and are securely held in place substantially unaffected by vibration.

Although I have illustrated and described a preferred construction, I do not intend to be limited to the precise details thereof as the scope of the invention is best defined in the appended claims.

I claim:

1. A socket assembly adapted to be mounted in an apertured support comprising a carrier member provided with a socket-receiving portion, a positioning member secured to said carrier member and having a positioning element extending outwardly therefrom providing surfaces for radially and circumferentially spaced relationship about a socket disposed in said socket-receiving portion for engaging the edges of an aperture in a support during the mounting of the socket assembly in such an apertured support, said positioning element having apertures extending through said surfaces, and a ring member associated with said carrier member having projections extending radially outward therefrom through said apertures.

2. A socket assembly adapted to be mounted in an apertured support comprising a carrier

member provided with a socket-receiving portion and an outwardly extending annular flange, a flange member secured to said annular flange and having positioning elements extending outwardly therefrom providing surfaces for radially and circumferentially spaced relationship about a socket disposed in said socket-receiving portion for engaging the edges of an aperture in a support during the mounting of the socket assembly upon such an apertured support, said positioning elements having apertures extending through said surfaces, and a ring member associated with said carrier member having projections extending radially outward therefrom through said apertures.

3. A socket assembly adapted to be mounted in an apertured support comprising a carrier member provided with a socket-receiving portion, a fastening and positioning member secured to said carrier member and comprising a flat ring portion provided with inturned spring fingers extending outwardly from the inner edge of said ring portion and providing surfaces for radially and circumferentially spaced relationship about a socket disposed in said socket-receiving portion for engaging the edge of an aperture in a support during the mounting of the socket assembly upon such an apertured support, said spring fingers having apertures therethrough communicating with spaced apertures in said ring portion, and a resilient ring member having ears thereon extending radially outward through the apertures in said spring fingers into the apertures in said ring portion.

4. A socket assembly in accordance with claim 3 having lateral extensions on the socket-receiving portion of said carrier member giving a wing nut effect to facilitate mounting the assembly in an apertured support.

5. A unitary socket assembly as set forth in claim 3 in which the resilient ring member is laterally bent to offset some of the ears with respect to other ears, the offset ears having at least one edge thereof curved to facilitate mounting on an apertured support.

6. A unitary socket assembly as set forth in claim 5 in which the ears which are not offset have portions thereof bent outwardly from the plane of the ring for locking engagement with an apertured support and other portions thereof curved to facilitate disengagement from said apertured support.

7. A unitary socket assembly as set forth in claim 3 in which some of the said ears and the adjoining ring portions are laterally bent out of the plane of the ring to form cam surfaces adapted to facilitate mounting the assembly on an apertured support.

8. A unitary socket assembly as set forth in

claim 6 in which some of the ears are provided with laterally extending locking lugs adapted for locking engagement with an apertured support, said locking lugs having tapered edges to facilitate removal of the assembly from the apertured support.

9. A socket assembly adapted to be mounted on an apertured support comprising a carrier member provided with a socket-receiving portion having a socket mounted therein, a flanged member secured to said carrier member and carrying inturned spring fingers provided with apertures, a resilient ring member mounted within said flanged member and having ears thereon extending through said apertures, said ring member having a permanent set therein whereby some of said ears are offset with respect to other ears, a supporting base member having an inturned flange provided with radial notches, said offset ears being adapted to be positioned in said radial notches and then rotated into clamping engagement with the inner side of said flange, to thereby secure the socket assembly to said supporting member.

10. A socket assembly adapted to be mounted on an apertured support comprising a socket-carrying member, a flanged member secured to said socket-carrying member and having inturned spring fingers extending outwardly therefrom for positioning the assembly in an apertured support, said inturned spring fingers having openings therethrough, a resilient ring member mounted on said socket-carrying member and having ears thereon extending through said apertures, certain of said apertures being relatively deep to permit movement of the ears therein away from said socket-carrying member for locking engagement with an apertured support, others of said apertures being relatively shallow to confine the ears therein closely adjacent the socket-carrying member, whereby movement of the ears in such relatively deep apertures into locking engagement with an apertured support places the ears in said shallow apertures under tension to firmly hold the assembly against the apertured support.
